US00D977823S

(12) **United States Design Patent** (10) **Patent No.:** **US D977,823 S**
van Middendorp (45) **Date of Patent:** **** Feb. 14, 2023**

(54) **BAG**

(71) Applicant: **Invented Here B.V.**, Ulft (NL)
(72) Inventor: **Christel van Middendorp**, Ede (NL)
(73) Assignee: **Invented Here B.V.**, Ulft (NL)

(**) Term: **15 Years**

(21) Appl. No.: **29/759,816**

(22) Filed: **Nov. 25, 2020**

(30) **Foreign Application Priority Data**

May 28, 2020 (EM) 007973417-0002

(51) **LOC (14) Cl.** **03-01**

(52) **U.S. Cl.**

USPC **D3/216**

(58) **Field of Classification Search**

USPC D3/213-217, 221, 224-226, 231, 232, D3/233, 242-244, 254, 255

(57) **CLAIM**

The ornamental design for a bag, as shown and described.

DESCRIPTION

FIG. 1 is a front perspective view of a bag showing my new design;

FIG. 2 is a front view thereof;

FIG. 3 is a rear view thereof;

FIG. 4 is a right side elevation view thereof;

FIG. 5 is a left side elevation view thereof;

FIG. 6 is a cross sectional view of the bag taken in the direction of line 6-6 of FIG. 4;

FIG. 7 is a cross sectional view of the bag taken in the direction of line 7-7 of FIG. 5;

FIG. 8 is a bottom plan view of the bag of FIG. 1; and, FIG. 9 is a top plan view of the bag of FIG. 1.

The dashed broken lines in the figures illustrate portions of the bag that form no part of the claimed design.

1 Claim, 9 Drawing Sheets
